UNITED STATES PATENT OFFICE.

SAMUEL OLSON, OF CHICAGO, ILLINOIS, ASSIGNOR TO SAMUEL OLSON & COMPANY, OF CHICAGO, ILLINOIS, A CORPORATION OF ILLINOIS.

TRAY ELEVATOR.

Application filed November 27, 1920. Serial No. 426,775.

To all whom it may concern:

Be it known that I, SAMUEL OLSON, a citizen of the United States, and having residence at Chicago, in the county of Cook 5 and the State of Illinois, have invented certain new and useful Improvements in Tray Elevators, of which the following is a specification, reference being had to the accompanying drawings forming a part thereof.

10 This invention relates to an elevator of the type shown and described in my Patent 1,325,857 issued December 23, 1919 and its purpose is to provide certain features of construction for an elevator of that type 15 which shall be efficient in operation and ordinarily less expensive to manufacture than the corresponding elements of the patented structure. The novel features are herein-after described and shown in the drawings 20 and are particularly indicated by the claims.

In the drawings:

Figure 1 is a sectional plan view of an elevator of the type to which this invention relates and illustrates one of the novel 25 features of construction.

Figure 2 is an elevation of the same, being taken partly in section.

Referring first to Figures 1 and 2, it will be noted that this type of elevator consists 30 of two pairs of chains, 1, mounted for vertical travel about suitable head wheels, 2, and foot wheels, 3, which are preferably toothed wheels for positive engagement with the chain links; and that said chains are 35 arranged in pairs, the two chains of each pair being connected by flights in the form of angle-shaped members whose vertical arms, 4, are attached to the links of the two chains while their horizontal arms extend 40 toward the opposite pair of chains and in horizontal registration with similar flights for supporting loads such as trays of the type commonly used in restaurants and cafeterias for carrying dishes. Thus each 45 pair of chains, 1, with its attached flights, constitutes a belt mounted for vertical travel and for steadyng these belts particularly at their load supporting flights, Figure 1 shows the vertical arms of the angular 50 flights extending beyond the horizontal arms to form guide following lugs, 6, which engage between vertically extending guides laterally adjacent the belts.

In the particularly arrangement shown 55 in Figure 1, a horizontally traveling belt,

7, passes between the vertically moving flights of the elevator for receiving trays therefrom as the flights descend past the plane of the belt, 7. The guideways for the lugs, 6, are shown as composed of angle 60 rails, 8, at what may be termed the rear side of the elevator and angle rails, 9, at the front side, the latter being nested so as not to project unduly toward the belt, 7, and into the path of trays as they are discharged from the elevator by said belt, 7. In my said Patent 1,325,857 the guide lugs on the flights are shown as offset away from the path of these trays at the front side of the elevator; but in the present construction 70 a similar result is obtained by fitting the vertical arms, 4, of the flights with spacing blocks, 10, whose exposed faces are thus offset from the lugs, 6, which extend straight in the plane of the arms, 4. In this way 75 the trays as they are moved off the horizontal arms, 5 onto the belt, 7, are spaced away from the lugs, 6, far enough to clear the overlapping parts of angle rails, 9, which engage the inner faces of the lugs, 6. 80

As indicated in Figure 2, each belt may present a practically continuous vertical wall if plates, 11, be attached to the chains, 1, to extend between the vertical arms, 4, of the flights. Each flight and each plate 85 is attached only to one link of each chain to permit unhampered travel of these parts around the wheels, 2 and 3.

I claim:

1. An elevator comprising a pair of vertically traveling belts running parallel to each other and each including transversely disposed members with extending end portions extending in the plane of said members, vertical guideways engaging said end portions to steady the belts in their travel, parts on each belt projecting laterally from said plane of the transverse members toward the other belt and in horizontal registration with each other for supporting 90 loads, and spacing blocks secured to the faces of the belts adjacents said horizontal projecting parts for the purpose indicated. 95

2. An elevator comprising two pairs of vertical traveling chains running parallel to each other, each pair being transversely connected by angle rails disposed at intervals in registration with similar rails on the opposite pair, said rails being secured to the chains, each with one arm extending ver- 100 105 110

tically and the other arm projecting horizontally to support a load, the vertical arms having end portions extending beyond the horizontal arms, vertical guides overlapping the inner faces of said end portions and spacing blocks secured to the opposing faces of said vertical arms to limit the load-re-

ceiving space between them so that it does not exceed the distance between the overlapping guides.

In testimony whereof, I have hereunto set my hand at Chicago, Illinois, this 17th day of November, 1920.

SAMUEL OLSON.
